FIG. 6.

UNITED STATES PATENT OFFICE

ROBERT A. FORESMAN, OF MOORES, AND DONALD J. MOSSHART, OF LANSDOWNE, PENNSYLVANIA, ASSIGNEES TO WESTINGHOUSE ELECTRIC AND MANUFACTURING COMPANY, A CORPORATION OF PENNSYLVANIA

TUYÈRE CONSTRUCTION

Application filed April 3, 1930. Serial No. 441,297.

My invention relates to underfeed stokers and more particularly to the so-called tuyère blocks for such stokers, and it has for an object to provide a tuyère block of improved construction.

In apparatus of this character heretofore known to me, particularly the downwardly inclined, multiple-retort underfeed stoker, it is usually the practice to provide adjacent 10 the retorts, a fuel-supporting and air-supplying means consisting of a plurality of hollow tuyère blocks disposed in overlapping, stacked relation and supported by the walls of the retort. The tuyères are usually provided with spaced, downwardly-extending flanges or fins which rest upon the upper surface of the tuyère therebelow and define separate uninterrupted passages for the air flowing from the interior to the exterior of 15 the tuyère.

Difficulty has been experienced in the use of the prior art constructions for the reason that the air flowing through the tuyère does not absorb sufficient heat to effectively prevent 20 the sticking of molten clinker and ash to the upper surface thereof.

More particularly, therefore, it is an object of this invention to provide a hollow tuyère block for underfeed stokers, which is so constructed as to provide a multitude of tortuous 25 passages for the air flowing to the fuel bed, so that such air will come into intimate contact with relatively large areas of the tuyère structure and thereby more effectively 30 absorb heat therefrom.

These and other objects are effected by my invention, as will be apparent from the following description and claims, taken in connection 35 with the accompanying drawings, forming a part of this application, in which:

Fig. 1 is a fragmentary view, partially sectional and partially side elevational, of a row of tuyères constructed in accordance 40 with the present invention;

Fig. 2 is a fragmentary plan view of a row of tuyères, and showing also, adjacent portions of the retorts;

Fig. 3 is a bottom plan view of three of 45 the tuyères in assembled relation;

Fig. 4 is an enlarged top plan view of one of the tuyères;

Fig. 5 is an enlarged bottom plan of the tuyère shown in Fig. 4; and,

Fig. 6 is a longitudinal sectional view 55 through the tuyère blocks shown in Figs. 4 and 5.

According to a preferred embodiment of the present invention, which is shown on the accompanying drawing, I provide an integrally-cast hollow tuyère block comprising a relatively thin plate-like body having embedded therein a wrought metal piece for strengthening the same, side portions depending from the forward lateral edges of 60 the body, and a plurality of rows of frustoconical-shaped projections depending from the side and rear portions of the body and being so arranged that the projections of one row are disposed in staggered relation 65 with respect to the projections of an adjacent row, thereby providing a multitude of interconnected, tortuous passages for conveying the air from the interior of the tuyère block. 70

By reason of this construction, it is necessary for the air to come into intimate contact with a number of the projections before reaching the fuel bed, thereby resulting in a relatively greater amount of heat absorption 75 by the air, and a relatively cool tuyère block. 80

Referring now in detail to the construction illustrated, it is to be observed that I have shown, in Figs. 1 and 2, a plurality of integrally-cast, hollow tuyère blocks 10 arranged in overlapping, stacked relation, and supported by the upper edges of side walls 11 of adjacent retorts 12 of a downwardly-inclined multiple-retort underfeed stoker. Air is supplied to the space between the retort sides 11 by any suitable means, not shown, and this air flows upwardly into the tuyère blocks and outwardly through passages provided in the tuyère blocks, and into the fuel bed for supporting combustion. 85

The tuyère block 10 comprises a relatively thin, plate-like body 13, side portions 14 depending from the rear lateral edges of the body and engaging the upper surfaces of the retort side walls 11, and a plurality of frustoconical-shaped projections 15 depending 90

from the side and rear portions of the body 13 and engaging the upper surface of the tuyère therebeneath. The body is provided with a centrally-arranged, longitudinally-extending slot 16 having a reinforcing rib 17. The body is also provided with a locking lug 18 extending downwardly therefrom and adapted to fit within slots 16 of the tuyères disposed therebeneath for holding the tuyères in their proper relative position. Wrought metal pieces 22 are embedded within the body 13 to serve as a strengthening means.

It is to be observed from an examination of Figs. 1 and 3 that alternate tuyères 10 are provided at their rearmost ends with downwardly-extending lugs 19 which cooperatively engage lugs 20 provided on the inner side of the side walls 11, to hold the tuyères in place. The remaining tuyères 10 are provided at their rearmost ends with downwardly-extending projections 21 which engage the rear end of the tuyère 10 therebeneath (see particularly Fig. 3).

Referring now in detail to Figs. 4 and 5, the frusto-conical-shaped projections 15 are arranged in rows indicated by the reference characters 15a, 15b, 15c, 15d and 15e, and the projections of any one of the rows are disposed in staggered relation with respect to the projections of adjacent rows, thereby providing a plurality of inter-connected tortuous passages for the air flowing from the interior of the tuyère block to the exterior thereof. By reason of this construction, it will be necessary for the air flowing through the tuyère to come into intimate contact with the sides of the projections 15, thereby providing for the effective transmission of heat from the tuyère block to the air.

In view of the above description and accompanying drawings, it will be readily seen that I have provided a relatively simple, rugged and inexpensive tuyère block, which is maintained at all times in a relatively cool condition by the air flowing therethrough. Furthermore, by reason of the fact that the tuyère blocks are relatively thin in construction, an extremely large area of air openings is provided per unit length of retort.

While we have shown our invention in but one form, it will be obvious to those skilled in the art that it is not so limited, but is susceptible of various changes and modifications without departing from the spirit thereof, and we desire, therefore, that only such limitations shall be placed thereupon as are imposed by the prior art or as are specifically set forth in the appended claims.

What we claim is:

1. An integrally-cast hollow tuyère block comprising a relatively thin, plate-like body, and a plurality of separate projections depending from the lateral and rear portions of the plate and so arranged as to provide a multitude of interconnecting tortuous air

passages connecting the interior of the casting with the exterior thereof.

2. An integrally-cast hollow tuyère block comprising a relatively thin, plate-like body, a wrought metal piece embedded within the body for strengthening the latter, and a plurality of separate projections depending from the lateral and rear portions of the plate and so arranged as to provide a multitude of interconnected tortuous air passages connecting the interior of the casting with the exterior thereof. 75

3. A hollow tuyère block for underfeed stokers adapted to be arranged in overlapping relation with similar tuyère blocks to provide a fuel-supporting and air-supplying means, and comprising, in combination, a plate-like body, side portions depending from the forward lateral edges of the body, and a plurality of separate projections depending from the side and rear portions of the body and so arranged with respect to one another as to define a multitude of interconnected tortuous air passages connecting the interior of the tuyère with the exterior thereof. 85

4. A hollow tuyère block for underfeed stokers adapted to be arranged in overlapping relation with similar tuyère blocks to provide a fuel-supporting and air-supplying means, and comprising, in combination, a plate-like body, side portions depending from the forward lateral edges of the body, a plurality of separate projections depending from the side and rear portions of the body and so arranged with respect to one another as to define a multitude of interconnected tortuous air passages connecting the interior of the tuyère with the exterior thereof, and strengthening means embedded within the plate-like body. 95

5. A hollow tuyère block for underfeed stokers adapted to be arranged in overlapping relation with similar tuyère blocks to provide a fuel-supporting and air-supplying means, and comprising, in combination, a plate-like body, side portions depending from the forward lateral edges of the body, and a plurality of rows of frusto-conical-shaped projections depending from the side and rear portions of the body and being so arranged that the projections of one row are disposed in staggered relation with respect to the projections of an adjacent row, thereby providing a plurality of tortuous air passages connecting the interior of the tuyère with the exterior thereof. 105

6. A hollow tuyère block for underfeed stokers adapted to be arranged in overlapping relation with similar tuyère blocks to provide a fuel-supporting and air-supplying means, and comprising, in combination, a plate-like body, side portions depending from the forward lateral edges of the body, a plurality of rows of frusto-conical-shaped projections depending from the side and rear

portions of the body and so arranged that the projections of one row are disposed in staggered relation with respect to the projections of an adjacent row, thereby providing a plurality of tortuous air passages connecting the interior of the tuyère with the exterior thereof, and strengthening means embedded within the plate-like body.

7. A hollow tuyère block for underfeed stokers adapted to be arranged in overlapping relation with similar tuyère blocks to provide a fuel-supporting and air-supplying means, and comprising, in combination, a plate-like body having a centrally-arranged, longitudinally-extending slot, side portions depending from the forward lateral edges of the body, a plurality of separate projections depending from the side and rear portions of the body and so arranged with respect to one another as to define a plurality of tortuous air passages connecting the interior of the tuyère with the exterior thereof, and a locking lug extending downwardly from the plate-like body and adapted to extend through the centrally-arranged slots of the tuyères arranged therebeneath.

In testimony whereof, we have hereunto subscribed our names this 31st day of March, 1930.

ROBERT A. FORESMAN.
